UNITED STATES PATENT OFFICE.

BERNHARD BLOCK AND ABRAHAM B. BLOCK, OF NEW YORK, N. Y.

DESIGN FOR A DISPLAY-STAND.

47,772.

Specification for Design. Patented Aug. 31, 1915.

Application filed June 23, 1915. Serial No. 35,977. Term of patent 7 years.

To all whom it may concern:

Be it known that we, BERNHARD BLOCK and ABRAHAM B. BLOCK, citizens of the United States, residing at New York, in the county of New York and State of New York, have invented a new, original, and ornamental Design for Display-Stands, of which the following is a specification, reference being had to the accompanying drawing, forming a part thereof.

The drawing is a perspective view of a display stand showing our design.

We claim:

The ornamental design for a display stand as shown.

BERNHARD BLOCK.
ABRAHAM B. BLOCK.

Witnesses:

HUGO MOCK,
MAE PERRY.
